UNITED STATES PATENT OFFICE.

EDWARD D. TEMPERLE AND HARRY A. TEMPERLE, OF ST. LOUIS, MISSOURI.

DIRIGIBLE HEADLIGHT.

Application filed June 6, 1921. Serial No. 475,202.

To all whom it may concern:

Be it known that we, EDWARD D. TEMPERLE and HARRY A. TEMPERLE, citizens of the United States, residing at the city of St. Louis, in the State of Missouri, have invented certain new and useful Improvements in Dirigible Headlights, of which the following is a specification.

This invention is a means for mounting the headlights of a motor car or the like, particularly a Ford machine, in such manner that the turning of the front wheels simultaneously turns the headlights. This causes the light from the headlights to precede the wheels in the exact direction in which the wheels are traveling, instead of, as at present, shooting off at a tangent to the path of the wheels, especially when the car is turning a corner or around.

In the accompanying drawings forming part of this specification, in which like numbers of reference denote like parts wherever they occur,

Figure 1 is a top plan view;

Figure 2 is a sectional view on the line 2—2 in Figure 1; and

Figure 3 is a sectional view on the line 3—3 in Figure 1.

The so-called radius (or connecting) rod 1 is attached to a pair of clamping-members 2 and 3, fastened together by bolts 4, whereby the said clamping-members 2 and 3 are firmly fixed or attached to rod 1. A set-screw 5 insures a bite on rod 1. A stud 6 is borne by the clamping-member 3 and is encircled by the eye 7 on the end of rod 8. A similar eye on the end of rod 9 rides on the said eye, and both are retained on stud 6 by cotter 10.

An eye 11 at the opposite end of rod 8 encircles a pin 12, which is held in place by its head and cotter 13 in fork 14 of casting 15, which casting is provided with fork 16 arranged at substantially a right angle to fork 14.

A pin 17 is fixed in fork 16 and is encircled by eye 18 on link 19, which at its opposite end is provided with eye 20 encircling pin 21, fixed in fork 22 of casting 23. A hole 24 passes through casting 23 and receives rod 25, which is held fast in hole 24 by set-screw 26.

The opposite end of rod 25 is sweated or otherwise suitably fixed in eye 27 on one end of a crank arm consisting of a casting 28, which at its other end is provided with

sleeve 29, which receives stud 30 projecting from the main casting 31. Stud 30 is held in sleeve 29 by set-screw 32.

The main casting 31 is composed of a standard 33 arranged at substantially a right angle to the body-portion 34, which body-portion is substantially the lid for a box 35. From the lid 34 project lugs 36, and from the box 35 project lugs 37. A hole pierces each pair of these lugs, and a screw 38 fastens the same together and unites the lid 34 to the box 35.

The box 35 when in position is turned upside down, so that the lid 34 is in effect its bottom. The box 35 is composed of a pair of castings 39 and 40, one of which possesses the lip 41. Both of the said castings are provided with lugs 42, which fit into notches 43 in plate or lid 34, so as to hold it and box 35 more tightly together. For the same reason, lid or plate 34 is provided with a flange 44, upon which the lower edge of box 35 rests.

Lugs 42 are bent inwardly, notches 43 in flange 44 being undercut beneath the main-body of plate or lid 34 and the said lugs 42 grip plate or lid 34 securely.

A collar 45 is formed on post 46, and a groove 47 lies between the same and boss 48. Semi-circular notches 49 in the casting 39 and 40 are located opposite each other so as to form a round hole that encircles post 46, and the edges of the said hole, that is to say, the edges of castings 39 and 40 where notches 49 are cut fit into groove 47.

Standard 33 is hollow. A shaft 50 is revolvably mounted therein and at its upper end bears a gear 52, which is fixed thereto and rotates therewith.

When the notches 49 are seated in the groove 47 the inside of the top-wall of box 35 rests upon the top of shaft 50, which projects slightly above mutilated gear 52.

With one end of box 35 resting on shaft 50 and its other end resting in groove 47 and with lugs 42 seated in notches 43 and hooked under plate or lid 34 the insertion of screws 38 in the holes through lugs 36 and 37 tightly fastens box 35 and lid 34 together and covers over gear 52 and the similar gear 51, and the idler gear 53 interposed between the said two mutilated gears 51 and 52. The said three gears are constantly in mesh, that is to say, the mutilated gears 51 and 52 with idler gear 53. They can not get out of mesh because of rotation of gears 51 and 52 so far

as to effect disengagement of them from idler gear 53, due to the fact that before such disengagement can occur one of the side teeth on gears 51 and 52 will strike the side-
6 wall of box 35.

When set-screw 54 is screwed home gear 52 moves with shaft 50. When set-screw 55 is screwed home the headlight 56 moves with gear 52. In daylight running set-screw 55
10 will be unscrewed by key 57, so as not to contact with post 46, which contains a recess 58 for the reception of the end of set-screw 55. A recess 59 in shaft 50 receives the inner end
15 of set-screw 54 when the same is screwed home.

When it is desired that the headlights 56 shall turn simultaneously with the turning of the wheels 60, the setscrew 55 is unloosened and the set-screw 54 is screwed home; but when as in daylight running it
20 is desired that the headlight 56 shall remain stationary, so as to avoid wear and tear on the gears 51 and 52 and 53, etc., set screw 55 is screwed home and setscrew
25 54 is unloosened.

When by means of the steering wheel (not shown in the drawings), the radius-rod is moved so as to turn the wheels 60 in one direction, the rods 8 and 9 move correspondingly but with a slight play as to angles, denoted by full and dotted lines in Figure 1, with the result of rotating shaft 50. If set-screw 54 be seated in recess 59, having been screwed home by key 57, the
30 movement of rods 8 and 9 will result in rotating shaft 50, by means of the intermediate parts through which they are connected. Rotation of shaft 50 actuates gear 52, drives idler gear 53, and actuates gear 51, fixed to
35 post 46. Thereby the headlight 56 is correspondingly moved. Movement of rods 8 and 9 in the opposite direction turns headlights 56 in the opposite direction. It is to be understood that just as there are two
40 headlights 56, so also the parts between rod 8 and headlight 56 are duplicated by rod 9 and the intermediate parts between it and its headlight 56.

Screw 61 fastens idler 53 to plate or lid
50 34. Nut 62 is screwed on the lower end of post 46 and holds the same in the opening through plate or lid 34 and boss 63.

A slot 64 is cut through one of the end walls of box 35 for the insertion of the key
55 57, so as to reach the set-screw 54. Set-screw 54 contains a recess 65 for the reception of the square end of key 57. Set-screw 55 is provided with recess 66 for the same purpose.

60 Washer 67 is interposed between nut 62 and the lower edge of boss 63.

The swiveled connection of link 19 to the forks 14 and 16, and the similar connection between rods 8 and 9 and their respective
65 castings 15, allows for the natural adjust-

ment that is necessary on account of spring action and the difference in angle between rods 8 and 9 and the radius rod 1, to which rods 8 and 9 are fixed by the clamp-members 2 and 3 and the set-screw 5. The said swiveled arrangement of the link 19 more particularly compensates for the spring action, while the difference of angularity of rods 8 and 9 relative to rod 1 is permitted by the pivoting of rods 8 and 9 on their respective pins 12.

Headlights 56 are suitably mounted in connection with post 46, so as to move therewith. Hole 24 through casting 23 and rod 25 and set-screw 26 provide vertical adjustability. This is augmented by stud 30 and sleeve 29 and set-screw 32.

The axle 67 and the chassis 68 and brace-
70 rods 69 may be of any usual or desired construction.

Having thus described this invention, we hereby reserve the benefit of all changes in form, arrangement, order, or use of parts, as it is evident that many minor changes may be made therein without departing
80 from the spirit of this invention or the scope of the following claims.

We claim:

1. A dirigible headlight comprising a bracket, a pair of circumferentially grooved shafts journaled in said brackets, one of said shafts having means for supporting a headlight and the other shaft having means of connection with the steering rod of a motor vehicle to be actuated thereby, a train of gearing connecting the said shafts in driving relation and including a fixed gear on one shaft and a loose gear on the other, a releasable locking element carried by the loose gear engageable in the groove of the gear-shaft and a similar element carried by the bracket for movement into engagement with the groove of the headlight shaft for locking same against rotation.

2. The combination with a radius rod of a clamp secured thereon, a rod pivotally connected to the clamp, a casting, coupling pins carried by the casting, one of said pins being positioned horizontally and the other vertically, the vertical pin connecting the casting to the aforesaid rod, a link connected at one end to the horizontal pin, a casting to which the other end of the link is connected, a vertically positioned rod carried by the last-mentioned casting and adjustable thereon lengthwise, means for fixing said casting on the rod, a shaft, a crank arm connected at one end to the shaft and having its other end connected to the rod, a supporting member having means for supporting the shaft, a gear on the shaft, a headlight, a rotatable supporting post for the headlight, and gearing between said post and the aforesaid gear.

3. A dirigible headlight comprising a

bracket having means for attachment to a vehicle, a pair of shafts journaled in said bracket, one of said shafts having means for supporting a headlight, means for connecting the other shaft to the steering mechanism of the vehicle for actuation thereby, a driving connection between the shafts, said connection including a fixed gear on one shaft and a loose gear on the other shaft, 10 a releasable locking element carried by the

loose gear and engageable with the shaft of said gear, and a releasable locking element carried by the bracket and engageable with the headlight shaft for locking the same against rotation.

15

In testimony whereof we hereunto affix our signatures.

EDWARD D. TEMPERLE.
HARRY A. TEMPERLE.
